UNITED STATES PATENT OFFICE.

EUGENE C. KINNEAR, OF EVANSTON, ILLINOIS, ASSIGNOR TO ANAKIN LOCK & ALARM CO., OF CHICAGO, ILLINOIS, A PARTNERSHIP COMPOSED OF JOHN H. TAFT, JOHN A. TAFT, AND ADRIAN S. AILES.

BURGLARPROOF AUXILIARY LOCK.

Application filed March 17, 1923. Serial No. 625,711.

To all whom it may concern:

Be it known that I, EUGENE C. KINNEAR, a citizen of the United States, residing in Evanston, in the county of Cook and State 5 of Illinois, have invented a new and useful Improvement in Burglarproof Auxiliary Locks, of which the following is a specification.

My present invention relates to auxiliary 10 locking devices for vault doors or the like and has for a principal object the provision of an improved and quick-acting device for both projecting a supplementary locking bolt and relocking the main bolt work of 15 the door in the event of an attack upon said door, either by punching or blowing out the combination lock, or burning through the body of the door.

A further important object is the provision 20 of a bolt work locking member so arranged with respect to the supplementary bolt that release of the latter serves to automatically and immediately cause operation of said member to insure effective locking 25 action.

Other objects and advantages of the invention will be apparent as it is better understood from the following description, which, taken in connection with the accompanying drawings, illustrates a preferred 30 embodiment thereof.

Referring to the drawings,

Figure 1 is a partial elevational view of the interior of a vault door;

Fig. 2 is a top plan view of one of the auxiliary locking devices, being taken substantially on the line 2—2 in Fig. 1;

Fig. 3 is a horizontal section, taken substantially on the line 3—3 in Fig. 1 and 40 showing the bolt work locking lug;

Fig. 4 is an enlarged longitudinal section of the auxiliary locking device, being taken substantially on the line 4—4 in Fig. 2;

Fig. 5 is a cross sectional view of said device, taken substantially on the line 5—5 in Fig. 4; and

Fig. 6 is a sectional view of a locking device as installed on the upper portion of the door, being taken substantially on the line 50 6—6 in Fig. 1.

Upon the drawings, the reference numeral 11 indicates a vault door, which may be of any of the usual types employed. The combination lock 12 is positioned on the interior

of the door and contains locking tumblers 55 operable from the outside by a rotary dial, or any preferred means. Main bolts 13 are provided on the door and are controlled by the combination lock in the well-known manner. Auxiliary locking devices, generally 60 indicated by the reference character 14, are provided in the present instance above and below the combination lock, and are operable in manner to be hereinafter described in the event that effort is made to gain access 65 to the vault by any of the methods commonly employed by burglars.

The bolts 13 extend through a bolt rail 15, extending inwardly from the door, and are connected together by a carrying bar 16 secured to said bolts by small bolts 17. A master lug, or arbor, 18 is secured to the carrying bar 16 and adapted to be held in locking position by means of the tumblers 70 of the combination lock, said lug being 75 adapted to be manipulated by an external handle when the combination is operated. The bolts, when projected to locking position, engage behind a door jamb 19. The locking devices constitute separate units, 80 similarly constructed except for the position of a releasing trigger to be hereinafter referred to and it is thought that a description of one of said units will suffice for an 85 understanding of both.

Each said unit consists primarily of a supplementary bolt 21 positioned in a sleeve, or casing, 22, which latter is screw-threaded into the bolt rail, as shown at 23, and held 90 in place by a lock nut 24. Said bolt 21 is recessed at 25 and is held retracted against the tension of a spring 26 bearing against an end part 27 rearwardly of the recess 25. A cap 28 is threaded onto the rear end of 95 the casing and is knurled exteriorly, as shown at 29. A trigger block 31 is positioned on the casing 22, just forwardly of the cap 28, and is adapted to be secured to a plate on the door by means of screws 32 and 33 extending through apertures 34 and 35. Said block is held in place upon the casing 100 by means of set screws 36.

A trigger 37 is provided to normally hold the bolt 21 in retracted position and it will be noted that this trigger must be differently positioned in the upper and lower locking units. In the lower unit, it is positioned as shown in Fig. 5, extending through an 105

aperture 38 from the top of the block, whereas the trigger on the upper device is arranged as shown in Fig. 6, extending upwardly through an aperture 39 in the lower 5 part of the block 31. A shoulder 41 is provided at the inner end of the trigger 37 and a screw 42 is positioned to close the aperture through which the trigger extends, a spring 43 being positioned within said aperture and bearing upon the head 41. A ring 44 is provided in the outer end of the trigger 37 and operating connections, to be now described, are secured in said ring.

A connection 45 extends from the ring 15 through guide rings 46 and 47, across the combination lock 12, and is anchored to a fixed part on the door at 48. A second connection 49 extends from the ring to the end of a spring 51, which has its opposite end 20 permanently connected to the door. A connection 51' extends upwardly from the spring 51 about a sheave 52 and thence about another sheave and down behind the bolt carrying bar, being directed behind the master lug 18 and again downwardly and around another sheave 52' and upwardly to the lower end of a second spring 53. It will be manifest that a pull exerted upon the connection 45, by disturbance of the 25 combination lock 12 either by punching or blowing, or otherwise causing abnormal movement of the rear plate on said lock, will cause the trigger 37 to be withdrawn, allowing the auxiliary bolt 21 to be projected to locking position. Similarly, if the 30 connection 51' should be severed, as by burning through with a torch, the spring 51 will cause the connection 49 to withdraw said trigger to discharge the device. A clip 54 35 is provided on the block 31 and is adapted to engage the outer end of the trigger 37 to prevent accidental release, as by slamming the door, though it is apparent that said clip is not of sufficient strength to prevent 40 operation of the device by disturbance of the connections as just described. As shown, said clips are secured in place by screws 55 and may be turned from ineffective 45 position to the effective, or operative, position shown in dotted lines in Fig. 5.

The inner end of the trigger extends 50 through an aperture 56 in the casing 22 and a slide 57 is positioned between said casing and the block 31, this slide being apertured 55 at 58 to correspond to the aperture 56 in the casing and being under the tension of a spring 59 which moves it when the trigger is withdrawn to position preventing the re-engagement of said trigger with the bolt 21 60 without manipulating said slide.

In the foregoing manner, the door is relocked by means of the supplementary bolt 21 with normally successful results, but I prefer also to employ an auxiliary locking 65 means or mechanism for relocking the main

bolt work or mechanism of the door, thus rendering the device more effective. For this purpose, I employ a gravity arm 61, which is pivoted at 62 on the lower end of the block 31. Said arm is normally held in 70 inoperative position by means of a slotted clip 63 engaging over the head of a screw 64 threaded into the auxiliary bolt. It will be manifest that discharge of the bolt will cause said screw to be disengaged from the 75 clip, permitting the arm 61 to drop down by gravity and by the force of a spring 65 which is connected at 66 to the lower side of the arm and at 67 to the block 31. Stop blocks 68 are secured to the carrying bar 16, 80 by means of screws 69, the position of these blocks being slightly below the outer ends of the arms 61 when the latter are in raised position. Release of said arms causes immediate engagement with the blocks 68 to 85 prevent withdrawal of the main bolts and it is to be noted that, in view of the position of said arm and the employment of the spring 65, this action will be practically instantaneous and thus will be effective against 90 efforts to throw the bolt mechanism before the arm could engage and thus the vault will be as effectively locked, and even more so than before operation of the device, since not only will the bolt work be held in locking 95 position, but the supplementary bolts 21 will be projected to locking position.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. The combination of a vault door or the like, having main locking bolt mechanism thereon, means on the door for controlling said mechanism, and an auxiliary locking device operable by disturbance of said controlling means or by burning through the door, said device comprising a separate bolt projectable into locking position, and separate means movable relatively to said separate bolt for engaging and locking said main bolt mechanism against withdrawal.

2. The combination of a vault door or the like, having main locking bolt mechanism thereon, means on the door for controlling said mechanism, and an auxiliary locking mechanism operable by disturbance of said controlling means or by burning through the door, said auxiliary locking mechanism comprising a separate bolt projectable into locking and engagement with the frame of the door and separate locking means releasable by movement of said

- separate bolt for locking said main bolt mechanism against withdrawal.
3. The combination of a door having main bolt work thereon, means for controlling and locking said bolt work, an auxiliary locking device, and an operating connection adapted upon disturbance to discharge said auxiliary lock, said auxiliary locking device including a supplementary bolt, a pivoted lug positioned horizontally beneath said bolt, and means operable by projection of the bolt for causing immediate engagement of said lug with a part of said bolt work to relock the latter.
- 15 4. The combination of a door having main bolt work thereon, means for controlling and locking said bolt work, and an auxiliary locking device including a supplementary bolt, means for discharging said bolt by an attack upon the door, and means releasably suspended from said bolt and operable by discharge thereof to engage and thereby relock said main bolt work.
5. The combination of a door having main bolt work thereon, means for controlling and locking said bolt work, and an auxiliary locking device including a supplementary bolt, means for discharging said bolt by an attack upon the door, and separate locking means releasably suspended from said bolt and operable by discharge thereof to relock said main bolt work, said bolt work including a part engageable by said last-mentioned means and said means being mounted in close relationship to said part and adapted for immediate engagement thereof.
- 40 6. The combination of a door having main bolt work thereon, means for controlling and locking said bolt work, and an auxiliary locking device, including a supplementary bolt, means for discharging said bolt by an attack upon the door, and means suspended from said bolt and operable by discharge thereof to relock said main bolt work, said bolt work including a part engageable by said last-mentioned means and said means comprising a gravity actuated lug arranged
- in close relationship to said part whereby immediate engagement with the latter is effected.
7. The combination of a door having main bolt work thereon, means for controlling and locking said bolt work, and an auxiliary locking device including a supplementary bolt, means for discharging said bolt by an attack upon the door, and means suspended from said bolt and operable by discharge thereof to relock said main bolt work, said bolt work including a part engageable by said last-mentioned means and said means comprising a gravity and spring actuated lug mounted in close relationship to said part whereby immediate engagement with the latter is effected.
- 10 8. The combination of a vault door or the like having a main locking bolt mechanism, control means on the door for controlling said locking bolt mechanism, and auxiliary locking mechanism operable by disturbance of said control means or by burning through the door, said auxiliary locking mechanism comprising a locking device for locking said main locking bolt mechanism, separate means for locking the vault door by engagement with the frame of the door, and means releasable by disturbance of the control means for locking said separate means in a retracted position, said locking device being controlled by said separate means.
- 15 9. The combination of a vault door, or the like, having a main locking bolt mechanism, means on the door for controlling said mechanism, and an auxiliary locking mechanism, said auxiliary locking mechanism comprising a bolt locking device for locking said main bolt mechanism, a door locking device for engaging the frame of the vault door, and a latch device operable by disturbance of said controlling mechanism for releasing said door locking bolt, said bolt locking device being held in a normal inoperative position by said door locking bolt and being released thereby upon operation thereof.

EUGENE C. KINNEAR.
